UNITED STATES PATENT OFFICE.

WALTER H. SHADEL, OF JOPLIN, MISSOURI.

DESIGN FOR A TRAFFIC SIGNAL.

Application filed June 8, 1928. Serial No. 27,048. Term of patent 3½ years.

To all whom it may concern:

Be it known that I, WALTER H. SHADEL, a citizen of the United States of America, residing at Joplin, in the county of Jasper, and State of Missouri, have invented a new, original, and ornamental Design for a Traffic Signal, of which the following is a specification, reference being had to the accompanying drawing, forming a part hereof.

The drawing is a perspective view of a traffic signal showing my design.

I claim:

The ornamental design for a traffic signal, as shown.
